BY *W. H. Platt* ATTORNEY

UNITED STATES PATENT OFFICE.

CLARENCE D. PLATT, OF BRIDGEPORT, CONNECTICUT.

ELECTRICAL CUT-OUT.

Application filed February 11, 1923. Serial No. 535,676.

To all whom it may concern:

Be it known that I, CLARENCE D. PLATT, a citizen of the United States of America, residing at Bridgeport, Fairfield County, Connecticut, have invented a new and useful Electrical Cut-Out, of which the following is a specification.

My invention relates to what are commonly termed cut-outs, receptacles, etc., and particularly to devices having what are termed screw shells for receiving fuse plugs, lamps, connectors, etc.

In certain types of these devices safety inspectors and engineers require that the terminal and live parts be covered or protected so that there is no danger of accidental contact, and the consequent danger to life and property. Some manufacturers provide bases which support the principal parts, and covers for protecting the metal portions. These covers are usually removable to facilitate wiring, and lazy or careless workmen frequently fail to replace the covers. In such cases, the live parts remain exposed. I propose to make it difficult to use such cut-outs without the covers, and to leave the parts in such condition that the absence of the cover will serve as an indication that the cut-out is not in proper condition.

For the above purpose, I mount the screw shell so that when the parts are properly assembled and protected the plug or lamp base or connector may be readily inserted or removed in the usual manner, but in case the cover is missing, the screw socket will turn freely on its support and thus make it very difficult to insert the plug or other form of connector as the screw socket will turn around freely with the plug. This loose condition will be noticeable to the most casual observer.

Figure 1 is a plan view of one form of cut-out embodying the improvements of my invention, one of the covers being broken away, and one of the screw shells removed.

Fig. 2 is an edge view and partial section.

Fig. 3 is an exploded view of the screw shell and connecting parts.

Fig. 4 is a perspective view of another form of receptacle.

In the forms shown in Figs. 1 and 2, the insulating base 5 carries a plurality of screw shells 6, each of which serves to receive a

fuse plug, lamp base, or other connector 30 (not shown), which for convenience will hereinafter be referred to as a plug. The center contact 7 constitutes the head of a screw. The circuit terminals 8 and 9 are normally protected by an insulating cover 30 10 held in place by one or more screws 11. The cover 10 is removable to provide access to the binding screws of the terminals for wiring purposes.

The screw shell 6 is provided with a base 65 flange 12 loosely supported in a recess in the base 5. A cupped washer member 13 has a flange which overstands the flange 12 of the shell and a projecting flange 14 which extends through the bottom of the screw 70 shell 6 and engages the inner end of the circuit terminal 8. An insulating disc 15 and a washer 16 are interposed between the outer flange of the cup shaped member 13 and the head of the screw 7 so that when 75 the member 7 is screwed down tight, the cup shaped member 13 will make a firm electrical engagement with the inner end of the terminal 8. When the parts are in this position, the flange 12 is spaced away from 80 the outer flange of the member 13 sufficiently to leave the screw shell 6 loose and freely rotatable. If any attempt is made to screw a plug into the socket 6, it is plain that the 85 socket will turn round and round with the plug instead of permitting the plug to screw down into the socket as it should if the conditions were proper. To prevent the shell 6 from turning when the cover 10 is in place, I provide the shell with one or more 90 projections 17, and the cover I provide with corresponding recesses 18. When the cover is applied with the projections 17 in the recesses 18, the shell cannot rotate but will be held stationary and the plug will then be 95 seated in the usual manner. When a plug is screwed into the shell it eventually presses against the center contact 7 and further rotation pulls the shell outwardly so that the flange 12 is drawn toward the flange 13 to 100 provide electrical contact. To insure contact between the flanges, I may interpose a spring washer 19, which, however, does not retard rotation of the screw shell.

It should be understood that the device 105 may take various forms and designs, for instance, the base may be round as shown at 20 in Fig. 4, and the cover 21 may be held

in place by one or more screws 22. In this case the screw shell 23 is loosely mounted as previously described.

I claim:

5. 1. A cut out comprising an insulating base, a screw shell rotatably carried thereby, a circuit terminal for said screw shell, a cover for said base to guard said terminal and the sides of said screw shell, and means 10 for preventing said screw shell from rotating when said cover is in place.

2. A cut out comprising, a base having a recess, a screw shell rotatably mounted in said recess and having a projection, a cover 15 detachably secured to said base and having a portion coacting with said projection to prevent said screw shell from rotating.

3. A device of the character described comprising, a base having a recess, a screw 20 shell loosely mounted in said recess, a circuit terminal in said recess, detachable means in said screw shell for effecting electrical contact between said screw shell and a part of said terminal, and a cover member protecting 25 said screw shell and preventing it from rotating.

4. A device of the character described comprising, an insulating base, a contact member secured thereto, a screw shell having 30 a flange, means for establishing an electrical connection between said flange and said contact member, a detachable insulating cover and means carried by said cover for preventing 35 rotation of said screw shell.

5. A construction of the character described comprising an insulating base, a contact member mounted thereon, a circuit terminal for said contact member, a center contact, a circuit terminal therefor, a cover 40 member for covering said terminals and having a passage in line with said contact member and said center contact, and a fuse plug receiving member movable with respect to said base, and means carried by said cover 45 for holding said fuse receiving member in electrical connection with said contact member and preventing rotation of said fuse receiving member.

6. A device of the character described 50 comprising, a base, two circuit terminals carried thereby, a rotatable screw shell having a sliding contact with a part of one terminal, a screw connected to the other terminal and loosely holding said screw shell 55 in place, and a cover for said terminals preventing said screw shell from rotating.

7. A device of the character described comprising, an insulating base, a contact carried thereby, a screw shell having a flange, a cupped washer engaging said contact and 60 overstanding said flange, a center contact screw and an insulating disc interposed between said screw and said washer.

8. A device of the character described comprising, an insulating base, a contact carried thereby, a screw shell having a flange, a cupped washer engaging said contact and overstanding said flange, a spring washer between said flange and said cupped washer, a center contact screw and an insulating disc 70 interposed between said screw and said washer.

9. A construction of the character described comprising an insulating base, a contact member mounted on said base, a circuit 75 terminal therefor, a center contact, a cover detachably secured to said base and covering said circuit terminal but having an opening in line with said center contact and said contact member, a screw shell held stationary by said cover and resilient connection between said contact member and said screw shell.

10. A construction of the character described comprising an insulating base, a contact member mounted thereon, a circuit terminal therefor, a center contact, a fuse receiving shell electrically connected to said contact member but movable with relation thereto, and a cover member surrounding 90 said shell and holding it in position to receive a fuse plug, so that it may be electrically connected to said contact member and said center contact when said cover is in place.

11. A construction of the character described comprising an insulating base, a center contact member, a circuit terminal connected thereto, a laterally disposed contact member, a circuit terminal connected thereto, a cover member adapted to cover said circuit terminals but having a passage for a fuse plug receiving shell, a shell in said passage and having a flange resting upon said contact member, said cover holding said shell in position to operatively receive a fuse plug and connect it with said contact member and said center contact when said cover is mounted on said base and means for detachably connecting said cover to said base.

CLARENCE D. PLATT.
